UNITED STATES PATENT OFFICE.

CHARLES F. MORSE, OF RANDOLPH, ASSIGNOR OF ONE-HALF TO JOSEPH D. DENISON, OF WEST RANDOLPH, VERMONT.

EXPANSION-PULLEY.

SPECIFICATION forming part of Letters Patent No. 352,062, dated November 2, 1886.

Application filed February 9, 1886. Serial No. 191,304. (No model.)

To all whom it may concern:

Be it known that I, CHARLES F. MORSE, a citizen of the United States, residing at Randolph, in the county of Orange and State of Vermont, have invented certain new and useful Improvements in Expansion-Pulleys, of which the following is a specification, reference being had therein to the accompanying drawings.

My invention relates to that class of machine-pulleys in which the diameter of the pulley can be readily varied at will, without affecting its stability or strength, for the purpose of increasing or decreasing its circumference or flat face, thereby more perfectly adapting it to the length of the belting used as well as to the speed of its revolution, and the objects of my invention are, first, to obviate the necessity of using belting of different lengths and the changing of the length of a single belt to meet the demand required, and, second, to enable the operator to vary exactly the speed of the pulley, as the change in its circumference may be little or great, according to the object desired to be accomplished. These objects I attain by constructing the rim of the pulley of metal, consisting of an elastic coil, preferably made of steel, and supported upon shoes on the extremities of the several spokes, the rim being prevented from slipping on the shoes by means of friction-rollers which intervene between the upper surface of the shoes and the spring-coil or rim. The spokes of the pulley are jointed, the two parts being rigidly connected together by right and left screws, by turning which the lengths of the spokes are susceptible of such variation as may be desired, and thereby cause the length or circumference of the rim or flat face of the pulley to be increased or diminished.

In the drawings, in which similar letters indicate like parts, Figure 1 is a side elevation, partly in section, of a pulley embodying my invention. Fig. 2 is a plan view of the same.

A is the rim or external face of the pulley. It is composed of a coil of steel, which is made to pass several times over the shoes B B, which are rigidly secured to the outer extremities of the jointed spokes C C, the other ends of which are attached to the hub D, which forms the bearing for the shafting. The ends of the coil-spring are made to taper gradually, so that

when the coil is in place between the lips or projecting sides b b of the shoes, the width of the flat face of the pulley thus formed will be practically the same throughout. In one or 55 more of the spaces d d, between the arc of the rim A and the central or flat portion of the shoes above the ends of the spokes C C, is placed transversely a friction-roller, E, which effectually holds the rim in place, and prevents 60 its slipping on the shoes as soon as it becomes tightly crowded between the rim and the end of the shoe B, upon which the rim A rests.

The spokes C C of the pulley are jointed at or near their centers, and the two parts e f are 65 rigidly connected by right and left screws F F in such a manner that, according as these screws are turned, the length of the spokes C C are increased or decreased to the extent desired, and the distance of the several shoes B B from the 70 hub D being thus correspondingly varied the length or circumference of the coiled spring or flat face of the pulley is increased or diminished, as the elasticity of the spring compels it to press tightly upon the shoes, thus maintaining 75 its stability and strength, whatever may be the diameter obtained. As this operation can be easily performed at any time when the pulley is at rest, it is evident that the pulley may be readily adapted to the length of the belting, 80 and exactly according to the circumference required for the speed desired.

All changes in the diameter of the pulley can be easily made without the necessity of removing the pulley from the shafting or changing 85 the belting.

The lips or sides b b of the several shoes B B are designed to be of the same height as the thickness of the rim or flat face A of the pulley, and they may be so extended as to form a 90 continuous outside guard to the rim. They may also be arranged with adjustable set-screws through their sides, to more rigidly hold the adjoining portions of the coil together, if so desired, without departing from the spirit 95 of my invention.

What I claim as my invention, and desire to secure by Letters Patent, is—

1. An expansion-pulley composed of a rim consisting of a metallic coil supported upon 100 shoes attached to the extremities of jointed spokes projecting from the hub, the two parts

of the spokes being rigidly connected by right and left screws in coupling-boxes, by means of which the length of the spokes and the circumference of the pulley are correspondingly varied, substantially as shown, and for the purpose described.

2. In an expansion-pulley, the rim A, consisting of a coil of steel having tapering ends, in combination with the shoes B B, friction roller E, jointed spokes C C, whose length can be varied by right and left screws in their coupling-boxes, and the hub D, substantially as and for the purpose set forth.

3. In combination with the coiled rim A of 15 an expansion-pulley, the shoes B B, having

sides b b, the spokes, hub, and friction-roller E, substantially as shown and described.

4. In an expansion-pulley, the hub D and rim, in combination with the jointed spokes C C, rigidly held by coupling-boxes provided 20 with right and left screws, and the shoes B B, attached to their extremities having sides b b, and set-screws, substantially as described, and for the purpose set forth.

In testimony whereof I do affix my signature 25 in presence of two witnesses.

CHARLES F. MORSE.
